OIL PUMP

Arne Feroy, New York, N. Y.

Application August 26, 1944, Serial No. 551,299

13 Claims. (Cl. 103—38)

1

This invention relates to oil pumps suitable for use in fuel injection systems of internal combustion engines.

Objects of the invention are to provide: an improved fuel injection system of simpler design, fewer parts, less weight, easier manufacture, and lower cost—a system adaptable to handle either fuel oil or gasoline; an oil pump adaptable for use either as a fuel injection pump or as a force-feed lubricator; a fuel injection pump operable with a single plunger to serve one or several or all the cylinders of the engine; an oil pump whose reciprocating parts are light in weight for low inertia at high speed; a fuel injection pump whose single moving plunger can both meter the fuel and distribute it to the several cylinders; a fuel injection system for a multicylinder engine with only a single lapped or close fitting pair of parts, easily replaceable, not even requiring any extreme precision or high cost in the single pair; an oil pump plunger and barrel in which the fit of the plunger in the barrel is not subject to high pump pressure but to supply pressure only; an oil pump in which the leakoff from the pump plunger returns at once to the supply; a fuel injection pump in which the plunger may be easily lubricated whether handling fuel oil or gasoline, and in which the end of the plunger handling gasoline may be relieved to avoid seizure; a fuel injection system operable with precision and control at high engine speeds; a simpler and more rugged cam and a simpler and cheaper spring to coact with the cam, to drive the pump plunger with precision at any engine speed, low or high; a cam having the form of a multiple screw-thread, providing broad surface contacts, and an air spring to coact with the cam in driving the plunger without danger of hysteresis and breakage at high speed; a fuel injection system in which the injection characteristic may be independent of engine speed, and one in which the nozzles may be of the simple orifice type; a fuel injection system in which the timing of the injection may be readily adjusted with or without changing the quantity of the charge; a fuel injection system capable of delivering identical amounts of fuel to the several cylinders, whether governed by variable stroke of the pump plunger or by the simpler method of throttling the supply of fuel to the pump; a fuel injection pump unit in which the fuel supply pump or the governor or both may be easily incorporated in the pump unit if desired.

These and other objects of the invention are

2

attained by constructions shown in the drawings in which

Fig. 1 is a longitudinal section of a fuel pump unit;

Fig. 2 is an end view of the unit shown in Fig. 1;

Fig. 3 is an elevation of the moving cam of Fig. 1 with part of the plunger;

Fig. 4 is a bottom view of the parts shown in Fig. 3;

Fig. 5 is a longitudinal section of another pump unit in which the elements are inverted from those shown in Fig. 1;

Fig. 6 is an end view of the pump unit shown in Fig. 5;

Fig. 7 is an elevation of the moving cam of Fig. 5, inverted;

Fig. 8 is a bottom view of Fig. 7;

Fig. 9 is a longitudinal section thru a pump unit of the same inversion as that of Fig. 1, with means for adjusting the timing of injection and for varying the stroke of the plunger to control the quantity of injection;

Fig. 10 is a section on the line 10—10 of Fig. 9;

Fig. 11 is a section on the line 11—11 of Fig. 9;

Figs. 12 and 13 are diagrammatic views illustrating the thread form of the cams used in the pump units.

Referring to Figs. 1—4, 13 and 12 of the drawings, the pump body is in two parts, 15 and 16. Shaft 20 is supported in journal bearings 21 in the pump body. Shaft 20 may drive directly gear pump 17 having gears 21, which pump may serve as a fuel supply pump to furnish fuel to supply chamber 29 either thru a passage drilled in pump body 16 or thru an outside pipe to fuel inlet 28.

Drive gear 22 is keyed to drive shaft 20, and meshes with driven gear 23 journalled on sleeve 24 which is fixed in pump body 15 by nut 25.

Integral with gear 23, lugs 33 mate with notches 43 in cam member 44, so that cam member 44 will turn with gear 23. Cam surfaces 45 on cam member 44 have the form of a multiple thread, and engage similar cam surfaces 54 on fixed cam member 55 with surface contacts as shown clearly in Figs. 13 and 12. Immediately after release of cams 45 and 54, it is obvious that they have practically complete annular contact, possible only with cams having the form of a screw thread.

The threads shown are triple threads, suitable for a pump serving three cylinders per revolution; other numbers may be used.

Pump plunger 35 is a close running fit in cylinder 36 which is received in pump body 16 and clamped in by cover 18 held to pump body 16 by

screws 26. Packing 19 seals fuel supply chamber 29 from gear and cam chamber 39, which latter must be supplied with lubricating oil.

Cam surfaces 45 and 54 coat to move plunger 35 in one direction, while it is moved in the opposite direction by floating piston 42 operable in sleeve 24 either by a coil spring 41 or by air or gas pressure fed into the chamber thru pressure inlet 40. The source of pressure may be one of the cylinders of the engine, feeding thru a check valve to inlet 40.

The head of plunger 35 is held in engagement with cam member 44 by piston 42, and plunger 35 rotates as it reciprocates, being keyed to cam member 44 by flats milled on its head engaging the slot in the raised portion of cam member 44 as shown at 31, Figs. 3 and 4.

When plunger 35 is raised as shown in Fig. 1, fuel supply chamber 29 is in communication with pumping chamber 31 by groove 30 in plunger 35. Groove 30 also serves to distribute fuel pumped from chamber 31 to the several fuel outlet passages 32 and 34 to the several engine cylinders.

Operation is readily understood. Drive shaft 20 and gear 22 drive gear 23 whose lugs 33 engaging notches 43 of cam member 44, cause cam member 44 to rotate, cams 45 and 54 coating with surface contacts to raise cam member 44 and plunger 35 while they are rotating, until the ends of the ramps on cams 45 and 54 are reached, when spring 41 or air spring pressure in chamber 46, pressing on piston 42, returns plunger 35 and cam member 44 to engage the ramps of cams 45 and 54 once more with almost complete surface contacts. The pumping action of this simultaneous reciprocation and rotation of plunger 35 is obvious. Fuel entering supply chamber 29 can flow thru groove 30 into pumping chamber 31. Then on the spring driven return stroke of plunger 35, groove 30 is timed to line up with the desired discharge passage 32 just as the shoulder of plunger 35 closes the inlet end of groove 30 by passing supply chamber 29 to begin injection. Thus the combined reciprocation and rotation of plunger 35 serves to pump and to distribute the fuel.

The surface contacts of cams 45 and 54 make it possible for the cams to stand up in long service, the screw-thread form of the cams being much superior to any cams having point or line contacts. Similarly the air spring can operate at higher speeds than a metallic spring; no coil spring can return the plunger more than four or five thousand cycles per minute, but no limit has yet been reached on the ability of the air spring to operate rapidly and with precision.

Control of the quantity of fuel injected at each stroke of plunger 35 can be had by throttling the supply of fuel to supply chamber 29. Adjustment of the timing of injection is made at the initial setting of fixed cam member 55 in pump body 16. More complete means for quantity control and timing adjustment are illustrated in Figs. 9, 10, and 11. Sleeve 56 threaded upon the outside of cylinder 36 may be rotated by rack 57 to adjust the length of stroke of cam member 44, to control the quantity of fuel pumped per stroke by plunger 35, sleeve 56 presenting a variable abutment 58 receiving the inner face of cam member 44 on its return stroke before engagement of the ramps of cams 45 and 54. To adjust the timing of injection, the rim of cam 55 may be notched as at 59 to engage the end of adjustment screw 51 which may be locked by nut 52 to set cam 55 in desired timing adjustment. More

elaborate controls for these adjustments could obviously be provided.

In the fuel pump illustrated in Figs. 1-4 and 9-11, the screw-thread cams lift the plunger on its suction stroke while injection is by spring pressure, independent of engine speed, promoting good starting and slow speed operation.

Some may prefer the inversion illustrated in Figs. 5-8 in which the suction stroke of plunger 85 is by spring action while injection is by cam action. The pump body is in two parts, 65 and 66. Shaft 70 is keyed to drive gear 71 meshing with driven gear 72 journalled on the outside of fixed cam 86 which is centered on pin 67 held in pump body 65. Integral with gear 72, lugs 73 engage notches 74 in cam member 75, so that cam member 75 will turn with gear 72. Cam surfaces 78 on cam member 75 have the form of a multiple screw-thread, and engage similar cam surfaces 87 on fixed cam member 86. Plunger 85 and cylinder 36 are similar to those of Figs. 1-4.

Cam surfaces 78 and 87 coat to move plunger 85 in one direction, while it is moved in the opposite direction by floating pistons 81 bearing on plate 82. Floating pistons 81 are pressed against plate 82 by air or gas pressure entering at 80 from one of the cylinders of the engine, feeding thru a check valve; alternately the air pressure may come from the starting air tanks or from any other convenient source. The head of plunger 85 is held in engagement with cam member 75 by plate 82, and plunger 85 rotates as it reciprocates, being keyed to cam member 75 by flats milled on its head engaging the slot in the raised portion of cam member 75 as shown at 77 in Figs. 7 and 8. To avoid damage to the pump if driven in reverse, the ends of the screw-thread ramps are preferably inclined, as shown at 79, Figs. 7 and 8, and also in Figs. 12 and 13.

When plunger 85 is raised by pistons 81 and plate 82, fuel supply chamber 29 can be in communication with pumping chamber 31 thru groove 30 in plunger 85. Plunger 85 is driven on its outward stroke by cams 78 and 87, and is shown in Fig. 5 at the end of its outward stroke. Operation is similar to that described for the pump of Figs. 1-4, except that it is reversed, the suction stroke being spring actuated and the injection stroke being cam driven.

Since a single plunger is used with identical action to serve the several cylinders of an engine, identical delivery of fuel to the several cylinders can be assured, even if the fit of the plunger in its barrel should not be as perfect as usually demanded. Moreover, as shown in Fig. 1, lubricating oil in chamber 39, required to lubricate the gears and cams, can be led as thru holes 38 and 48 and groove 49, to lubricate plunger 35 in cylinder 36 to any desired degree, making the pump adaptable to handle gasoline as well as fuel oil; the pumping end of plunger 35 may be relieved slightly to prevent contact with barrel 36 when gasoline is being pumped.

There is little or no tendency of the fuel to leak past plunger 35 into chamber 39 because chamber 29 is the fuel supply chamber in which the fuel is never under high pressure. With spring injection, as in the pump of Figs. 1-4 and 9-11, it is well-known that only simple orifice nozzles are needed since the rate of injection is independent of engine speed. Simplicity of the fuel pump together with simple orifice nozzles combine to form a clean and simple fuel injection system of low cost, possibly low enough to compete with the carburetor on automobile engines.

Having thus described the invention and its operation, it is readily seen that the objects of the invention as stated have been attained. While specific embodiments of the invention have been shown and described, it is understood that changes may be made in the construction and in the arrangement of the various parts without departing from the spirit or scope of the invention as set forth in the following claims.

I claim:

1. In an oil injection pump for an engine, a pump plunger, a cylinder barrel receiving said plunger, and means for reciprocating said plunger in said barrel to inject oil into said engine, said means including a pair of cam members coaxial with said plunger, one cam member normally fixed and the other cam member rotating and engaging said fixed cam member with surface contacts formed as parts of multiple screw-threads.

2. In an oil injection pump for an engine, a pump plunger, a cylinder barrel receiving said plunger, and means for reciprocating said plunger in said barrel to inject oil into said engine, said means including a pair of cam members coaxial with said plunger, one cam member normally fixed and the other cam member rotating and engaging said fixed cam member with surface contacts formed as parts of multiple screw-threads to move said plunger in one direction, and spring means tending to maintain said cam members in engagement and operable to move said plunger in the other direction.

3. In an oil injection pump for an engine, a pump plunger, a cylinder receiving said plunger, and means for reciprocating said plunger in said cylinder to inject oil into said engine; said means including a pair of cam members coaxial with said plunger, one cam member normally fixed and the other cam member rotating and engaging said fixed cam member with surface contacts formed as parts of multiple screw-threads, said surface contacts symmetrically disposed about the axis of said plunger, and an air spring opposing the action of said cam members and comprising an expansible chamber enclosing air or gas under pressure.

4. In an oil injection pump for an engine, a pump plunger, a cylinder receiving said plunger, and means for reciprocating and rotating said plunger in said cylinder to inject oil into said engine and to distribute said oil to a series of parts of said engine during each revolution of said plunger, said means including a pair of cam members coaxial with said plunger, one cam member rotating with said plunger and the other cam member normally fixed, said cam members engaging each other with surface contacts formed as parts of multiple screw-threads, said surface contacts symmetrically disposed about the axis of said plunger.

5. In an oil injection pump for an engine, a pump plunger, a cylinder receiving said plunger, and means for reciprocating and rotating said plunger in said cylinder to inject oil into said engine and to distribute said oil to a series of parts of said engine during each revolution of said plunger, said means including a pair of cam members coaxial with said plunger, one cam member normally fixed and the other cam member rotating with said plunger and engaging said fixed cam member with surface contacts formed as parts of multiple screw-threads, and spring means tending to maintain said cam members in contact with each other.

6. In an oil injection pump for an engine, a pump plunger, a cylinder receiving said plunger, and means for reciprocating and rotating said plunger in said cylinder to inject oil into said engine and to distribute said oil to a series of parts of said engine during each revolution of said plunger, said means including a pair of cam members coaxial with said plunger, one cam member rotating with said plunger and the other normally fixed, said cam members engaging each other with surface contacts formed as parts of multiple screw-threads, said surface contacts symmetrically disposed about the axis of said plunger, and an air spring opposing the action of said cam members and comprising an expansible chamber enclosing air or gas under pressure.

7. In an oil injection pump for an engine, a pump plunger, a cylinder barrel receiving said plunger, and means for reciprocating said plunger in said barrel to inject oil into said engine, said means including a pair of cam members coaxial with said plunger, one cam member normally fixed and the other cam member rotating and engaging said fixed cam member with surface contacts formed as parts of multiple screw-threads, and spring means comprising a piston and cylinder with air or gas pressure acting therewith and tending to hold said cam members in engagement, said spring means driving said plunger on its pressure stroke to inject oil, and said cam members coacting to drive said plunger on its return or suction stroke.

8. In an oil injection pump for an engine, a pump plunger, a cylinder barrel receiving said plunger, and means for reciprocating said plunger in said barrel to inject oil into said engine, said means including a pair of cam members coaxial with said plunger, one cam member normally fixed and the other cam member rotating and engaging said fixed cam member with surface contacts formed as parts of multiple screw-threads, and spring means comprising a piston and cylinder with air or gas pressure acting therewith and tending to hold said cam members in engagement, said cam members coacting to drive said plunger on its pressure stroke to inject oil, and said spring means driving said plunger on its return or suction stroke.

9. In an oil injection pump for an engine, a pump plunger, a cylinder barrel receiving said plunger, and means for reciprocating said plunger in said barrel to inject oil into said engine, said means including a pair of cam members coaxial with said plunger, one cam member normally fixed and the other cam member rotating and engaging said fixed cam member with surface contacts formed as parts of multiple screw-threads, and means for varying the stroke of said plunger to control the quantity of oil delivered.

10. In an oil injection pump for an engine, a pump plunger, a cylinder barrel receiving said plunger, and means for reciprocating said plunger in said barrel to inject oil into said engine, said means including a pair of cam members coaxial with said plunger, one cam member normally fixed and the other cam member rotating and engaging said fixed cam member with surface contacts formed as parts of multiple screw-threads, and an adjustable abutment coacting with said rotating cam member to vary the stroke of said plunger to control the quantity of oil delivered.

11. In an oil injection pump for an engine, a pump plunger, a cylinder barrel receiving said plunger, and means for reciprocating and ro-

tating said plunger in said barrel to inject oil into said engine and to distribute said oil to a series of parts of said engine during each revolution of said plunger, said means including a pair of cam members coaxial with said plunger, one cam member normally fixed and the other cam member rotating with said plunger and engaging said fixed cam member with surface contacts formed as parts of multiple screw-threads, in combination with spring means tending to maintain said cam members in contact with each other, and an adjustable abutment coating with said rotating cam member to vary the stroke of said plunger to control the quantity of oil delivered.

12. In an oil injection pump for an engine, a pump plunger, a cylinder receiving said plunger, and means for reciprocating and rotating said plunger in said cylinder to inject oil into said engine and to distribute said oil to a series of parts of said engine during each revolution of said plunger, said means including a pair of cam members coaxial with said plunger, one cam member normally fixed and the other cam member rotating with said plunger and engaging said fixed cam member with surface contacts formed as parts of multiple screw-threads, in combination with an air spring comprising a cylinder and a piston floating therein and bearing against said plunger, means for adjusting said normally fixed cam member to adjust the timing of injection, and a movable abutment coating with said rotating cam member to vary the stroke of said plunger to control the quantity of oil delivered.

13. In an injection pump for an engine, a 35

pump plunger, a cylinder barrel receiving said plunger, cam means for driving said plunger on its suction stroke, and spring means operable upon the release of said cam means for driving said plunger on its delivery stroke in an abrupt manner independent of the speed of said engine, said cam means coaxial with said plunger and comprising a pair of similar cam members one rotating with said plunger and the other normally fixed, said cam members engaging each other with surface contacts as numerous as the number of cycles of operation of said plunger per revolution thereof.
